Clark Westover
BY *Victor J. Evans*
and Co. ATTORNEY
INVENTOR

WITNESS:

UNITED STATES PATENT OFFICE

CLARK WESTOVER, OF WAUCONDA, WASHINGTON

TREE PROP

Application filed May 20, 1931. Serial No. 538,815.

My present invention has reference to a prop or support for overloaded branches of fruit trees, and my object is the provision of a device for this purpose that has a forked end in which the branch of the tree is received and which forked end is of such construction and arrangement as to direct the weight of the tree limb equally between both of the arms afforded thereby.

10. A further object is the provision of a device for this purpose in which the forked end of the device is provided by cutting angularly one face at the upper end of the prop proper and to pass through an angle opening in the prop at the said end a pin which may be of such length or connected to the prop at such points as to vary the width of the yoke or notch and thereby compensate for different thicknesses of tree limbs.
15. A further object is the provision of a device for this purpose provided with a yoke or notch at its upper end in which is arranged a cushioning strip that will prevent injury to the branch of the tree received in said yoke or notch.

To the attainment of the foregoing the invention consists in the improvement herein-after described and definitely claimed.

In the drawing:

30. Figure 1 is a side elevation of the improvement.

Figure 2 is an end view thereof.

Figure 3 is a top plan view of the cushioning strip.

35. Figure 4 is a side elevation illustrating a slight modification.

As disclosed by the drawing I make use of an upright in the nature of a prop proper which is indicated by the numeral 1. The lower end of this upright 1 is pointed, as at 2, so that the same may be readily inserted in the ground opposite the tree which is overloaded with the fruit. The prop 1, from its upper end, has one of its faces cut angularly, as at 3, and from and adjacent to the lower end of the said angle face is provided with a laterally extending downwardly inclined round opening 4. I pass through this opening a cross sectionally round wooden member in the nature of a pin 5 and when the pin

has one end passed through the opening and its other end disposed opposite the angle face 3 of the prop a substantially V-shaped yoke is supported between these parts that receives therein the overladen limb of the tree. 55 A wire 6 is wound around the lower projecting end of the pin 5, twisted upon itself and from thence wound around the prop and has its ends connected. In this manner it will be noted that the pin is adjustably secured on 60 the prop so that the portion of the pin projecting beyond the angle face 3 of the prop may be extended to desired lengths to permit of the device receiving in the yoke or notched portion thereof tree branches of different 65 thicknesses.

Preferably I attach to the upper wall of the angle face 3 of the prop, by means 7, one end of a cushioning strip 8. The cushioning strip, adjacent to the second end thereof is 70 provided with a round opening 9 through which the pin 5 is passed. The portion of the cushioning strip provided with the opening is arranged at an angle with respect to the pin which permits of the adjustment of 75 the strip on the pin and which likewise holds the cushioning strip from movement when so adjusted.

In Figure 4 of the drawing the device is substantially similar to that just described, 80 except that in lieu of the wire 6 nails 10 are passed in opposite directions through the pin 5 to enter the prop.

The simplicity of the construction and the advantages thereof will, it is thought, be 85 apparent so that further detailed description will not be required.

Having described the invention, I claim:

1. A tree prop for the purpose set forth, comprising a prop member having one end pointed for insertion in the ground, its second end being cut angularly on one of its faces, and a pin member inserted angularly through the prop adjacent to its said upper end and means for adjustably securing said 90 pin on said prop.

2. A tree prop for the purpose set forth, comprising a prop member having one end pointed for insertion in the ground, its second end being cut angularly on one of its 100

faces, and a pin member inserted angularly through the prop adjacent to its said upper end and means for adjustably securing said pin on said prop and a cushioning strip having one end fastened to the angle end of the prop and its other end adjustably mounted on the pin.

3. A tree prop for the purpose set forth, comprising a prop member having one end pointed for insertion in the ground, its second end being cut angularly on one of its faces, a pin member inserted angularly through the prop adjacent to its said upper end and means for adjustably securing said pin on said prop, and a cushioning strip having one end fixed to the angle face of the prop and its second end provided with an opening to receive the pin therethrough.

In testimony whereof I affix my signature.

CLARK WESTOVER.
